United States Patent Office

Des. 189,488
Patented Dec. 27, 1960

189,488

TONGS

Richard J. Page, Minneapolis, Minn., assignor to Foley Manufacturing Company, Minneapolis, Minn., a corporation of Minnesota

Filed July 1, 1960, Ser. No. 61,194

Term of patent 14 years

(Cl. D44—4)

Fig. 1 is a perspective view of tongs showing my new design;

Fig. 2 is a top plan view;

Fig. 3 is a side elevational view;

Fig. 4 is an end elevational view on line 4—4 of Fig. 2;

Fig. 5 is a sectional view on line 5—5 of Fig. 2; and Fig. 6 is a sectional view on line 6—6 of Fig. 2. I claim:

The ornamental design for a tongs, as shown.
